UNITED STATES PATENT OFFICE.

JOHN N. WARREN, OF EAST ORANGE, NEW JERSEY, ASSIGNOR TO RADIO FREQUENCY LABORATORIES, INC., A CORPORATION OF NEW JERSEY.

VACUUM-TUBE CIRCUIT.

Application filed March 17, 1925. Serial No. 16,092.

The primary object of this invention is to stabilize the electrical conditions in a vacuum tube in such manner that the grid will be affected solely by the incoming radio wave impressed thereon, and to eliminate distortions caused by electrical strains set up from other sources, such as potential variations at the plate. Further objects and advantages of the invention, however, will be in part obvious and in part specifically referred to in the description herein-after contained, which taken in connection with the accompanying drawings, discloses the principles of the invention as applied to the circuits of a radio receiving system. In the drawings—

The single figure is a diagrammatic view of a radio receiving system adapted to function in accordance with the invention.

It should be understood that the present disclosure is merely typical as regards the receiver as a whole and the latter accordingly will not be described in detail, except as regards the particular features thereof which have to do with the present invention.

I have found that the current leaving the grid can be controlled by taking the filament leads through a coil of the same inductance as that which is connected to the plate in such a way that the electrical strain produced at the end of one inductance is counteracted by an opposite and equal strain at the end of the other inductance. Furthermore by magnetically coupling the inductances above mentioned, the electrical strain from the plate to the grid will be counteracted by the strain from the grid to the filament, thereby preventing a current flow from the grid in the grid circuit. In other words the plate or filament will not react upon the grid, regardless of what the tube capacities are, and the tube will therefore give true amplification throughout its working range and will work at maximum efficiency.

As applied to the first tube 1 of the system shown in the drawings, the lead 2 of the plate is connected to the inductance 3 which forms one of the primaries of the coupling coil for the next stage, coils 6 and 7 constituting other primary, and the leads 4 and 5 of the filament are connected respectively to the inductances 6 and 7, both of which are of the same value as the in-

ductance 3 previously mentioned. The inductance to be employed in coils 3, 6 and 7 is not at all critical so long as the resistance thereby interposed in the filament circuit is not so large as to interfere with proper heating of the filament. It will be noted that the coils 6 and 7 are so related and connected in circuit as to counteract each other as regards the "A" battery current but are cumulative for the radio current. In some instances the coils 6 and 7 may be replaced by a single coil included in the negative filament lead.

The inductances 3^a, 6^a and 7^a of the second tube 2 function in the manner above described and are similarly related. While the coils 3^b, 6^b, and 7^b of tube 3 in the next stage of amplification, and the coils 3^c, 3^d, 6^c and 7^c of the tube 4 of the last stage, function in the same manner, both are connected and related in a somewhat modified way on account of the different circuit conditions under which they operate.

It will be noted that the inductances are so connected that any "A" battery voltage variations will be neutralized and that the filament potential as regards the grid and plate will be held at an intermediate value. Furthermore since under the conditions above set forth no out of phase currents will be produced, it is possible to polarize the transformer coils in such a way that the magnetic interference between them will be a minimum.

While the invention has been disclosed as applied to certain particular circuits it will be obvious that many changes may be made therein without departing from its principles as set forth in the appended claims.

I claim:

1. A system of electrical circuits including a three electrode vacuum tube, having means for preventing reactions from the plate filament circuit back onto the grid comprising inductances in the plate and filament leads balancing strains from the plate to the grid by those from the filament to the grid.

2. A system of electrical circuits including a three electrode vacuum tube and means for preventing reactions from the plate filament circuit back onto the grid, wherein the filament leads include substantially equal inductances, and the plate lead also includes

inductance cooperating therewith to balance strains from the plate to the grid by those from the filament to the grid.

3. A system of electrical circuits including a three electrode vacuum tube and means for preventing reactions from the plate filament circuit back onto the grid, wherein the plate circuit includes an inductance and the filament circuit includes a counterbalancing inductance of substantially equal value.

4. A system of electrical circuits including a three electrode vacuum tube and means for preventing reactions from the plate filament circuit back onto the grid, wherein the plate circuit includes an inductance and the filament circuit includes a counterbalancing inductance of substantially equal value, said inductances being magnetically coupled.

5. A system of electrical circuits, comprising successive stages each including a three electrode vacuum tube and with magnetic couplings between stages, means in said stages for balancing strains from grid to plate by those from grid to filament, said means forming a part of the magnetic couplings aforesaid the secondary of one coupling being so connected to the succeeding

stage as to polarize the primary of the second stage with respect to the primary of the first stage.

6. A system of electrical circuits including a three electrode vacuum tube and means for preventing reactions from the plate filament circuit back onto the grid, wherein the filament leads include substantially equal inductances, and the plate lead also includes inductance cooperating therewith to balance strains from the plate to the grid by those from the filament to the grid, said first mentioned inductances being magnetically coupled.

7. A system of electrical circuits including a three electrode vacuum tube, having means for preventing reactions from the plate filament circuit back onto the grid comprising inductances in the plate and filament leads balancing strains from the plate to the grid by those from the filament to the grid, said inductances being magnetically coupled.

In testimony that I claim the foregoing, I have hereunto set my hand this 10th day of March, 1925.

JOHN N. WARREN.
